Attest,

UNITED STATES PATENT OFFICE.

GUSTAF M. ANDERSSON, OF WATERLOO, IOWA, ASSIGNOR TO ASSOCIATED MANUFACTURERS COMPANY, OF WATERLOO, IOWA, A CORPORATION OF IOWA.

OILING SYSTEM.

1,387,637.

Specification of Letters Patent. Patented Aug. 16, 1921.

Application filed May 23, 1919. Serial No. 299,271.

To all whom it may concern:

Be it known that I, GUSTAF M. ANDERSSON, a subject of the King of Sweden, residing at Waterloo, in the county of Blackhawk and State of Iowa, have invented certain new and useful Improvements in Oiling Systems, of which the following is a specification.

My invention relates to oiling systems, and 10 more particularly to such systems as apply to centrifugal separators, and the like.

The object of my improvement is the provision of means for directing the oil in a centrifugal separator through a filtering element and cause the filtered oil to pass through the bearings of the separator and other parts to be oiled, then re-conducted to the filtering medium.

Other objects will appear hereinafter.

20 An embodiment of my invention is shown in the accompanying drawing, forming a part of this specification, and in which the figure represents a central section of a cream separator, or the like, embodying my invention.

In the drawing I have illustrated a casing 1 in which is mounted a vertical spindle 2 carrying at its top a separator bowl 3 and mounted in suitable bearings 4. The spindle 2 is provided with a worm meshing with a worm wheel 5, and the latter is mounted on a drive shaft 6. The casing 1 is provided with a filling opening 7 and a drain opening controlled by a valve 8.

35 The casing 1 is formed so that one of its sides 9 is close to and substantially concentric with a portion of the worm wheel 5 so that as the worm wheel travels in the direction of the arrow 10 oil will be carried up 40 from the lower portion of the wheel and discharged by centrifugal force in the direction of arrow 11 against the side 12 of the casing. This oil will then descend by gravity down the side 12 and fall on a filter element 13. This filter material may be of 45 felt, or any other desirable substance suitable for properly cleaning the oil. The material 13 is preferably held away from the bottom of the oil well 14 by a perforated 50 plate 15. The perforated plate may be woven wire or material perforated so that the oil may pass freely through it after leaving material 13. The oil level in the casing 1 should not be above the plate 15.

55 In the bottom at one edge of well 14 is

a passage 16 which leads both to an opening 17 adjacent the spindle 2 and to a passage 18 down through or around bearing 4 and up to an opening 19 adjacent the lower part of the worm wheel 5 so that the passage of oil from well 14 may be down through bearing 4 and over the top of same to the worm wheel 5 as the latter draws the oil up against side 9 of the casing 1.

With this construction it will be apparent that most of the oil passes through the filter 13 as it circulates in the manner above mentioned. Some of the oil will, of course, fall before reaching side 12 and engage the worm on spindle 2 and fall directly to the bottom of the casing above bearing 4.

While I have illustrated and described the preferred form of my invention, I do not desire to be limited to the precise details set forth, but desire to avail myself of such variations and changes as come within the scope of the appended claims.

I claim:

1. A centrifugal separator comprising a casing having a well in its lower side; a wheel in the casing adapted to lift oil from the lower side of the casing and direct such oil against the casing above said well, said well being adapted to receive substantially all the oil directed against said casing; a support across said well; and filter material on said support in said well, there being a passage from said well to a position adjacent the lower part of said wheel.

2. A centrifugal separator comprising a casing; a bearing in said casing; a well above said casing with a passage leading from said well along said bearing for conducting oil to the latter; filter material in said well; and means for lifting oil from the bottom of said casing adjacent said bearing and delivering said oil to said well.

3. A centrifugal separator comprising a casing; a bearing in said casing having a passage extending along opposite sides thereof; a well at one side of said bearing with a passage opening into the passage associated with said bearing; a filter in the upper portion of said well; and a wheel in said casing adapted to lift oil from adjacent said bearing and discharge said oil against the interior of the casing above said well.

4. A centrifugal separator comprising a casing; a bearing in said casing; a shaft in said bearing, there being a passage along the

shaft in the bearing; a well connected with one end of said passage; means for moving the oil from the other end of said passage to said well; and a filter in the well.

5. A centrifugal separator comprising a casing having an oil reservoir at its bottom side; a bearing in said casing; a substantially vertical shaft in said bearing, there being a passage in the bearing along said 10 shaft with one end of said passage opening

in said reservoir; a well in the casing above oil in said reservoir and communicating with the other end of said passage; a wheel running in the oil of said reservoir and adapted to move said oil to said well; and 15 a filter in the well.

In testimony whereof I have signed my name to this specification on this 19th day of May, A. D. 1919.

GUSTAF M. ANDERSSON.
